(57) **CLAIM**

I claim the ornamental design for a curved light fixture, as shown and described.

DESCRIPTION

FIG. 1 is a bottom perspective view of a first embodiment of my new design comprising a curved light fixture;

FIG. 2 is a rear perspective view of the curved light fixture of FIG. 1;

FIG. 3 is a rear view of the curved light fixture of FIG. 1;

FIG. 4 is a front view of the curved light fixture of FIG. 1;

FIG. 5 is a left side view of the curved light fixture of FIG. 1;

FIG. 6 is a right side view of the curved light fixture of FIG. 1;

FIG. 7 is a top view of the curved light fixture of FIG. 1; and,

FIG. 8 is a bottom view of the curved light fixture of FIG. 1.

The broken lines illustrating portions of the light fixture form no part of the claimed design.

1 Claim, 4 Drawing Sheets
